SPRINKLER

John A. Royer, Fresno, Calif.

Application October 29, 1946, Serial No. 706,393

4 Claims. (Cl. 299—61)

1

This invention relates in general to an improved water sprinkler for lawns or the like.

In particular the invention is directed to, and it is an object to provide, a sprinkler of the rotary head type which includes novel water actuated impelling means to cause automatic rotation of said head when the sprinkler is in use.

Another object of the present invention is to provide a sprinkler wherein the rotary head is normally concealed and protected against damage, but is arranged to automatically pop up or elevate to an exposed position for operation when water under pressure is delivered to the sprinkler.

A further object of the invention is to accomplish the automatic rotation and pop-up features of the sprinkler through the medium of a simple but unique combination of cooperative parts.

An additional object of the invention is to provide a sprinkler, of the type described, which is designed so that its operation is not impaired by foreign substances, such as sand, which may be carried into the sprinkler by the stream of water.

A further object of the invention is to provide a simple and inexpensive device, and yet one which will be exceedingly effective for the purpose for which it is designed.

These objects are accomplished by means of such structure and relative arrangement of parts as will fully appear by a perusal of the following specification and claims:

In the drawings:

Fig. 1 is a sectional elevation of the novel sprinkler.

Fig. 2 is a cross sectional view on line 2—2 of Fig. 1.

Fig. 3 is a cross sectional view on line 3—3 of Fig. 1.

Fig. 4 is a bottom plan view of the impeller and stream unit, detached.

Referring now more particularly to the characters of reference on the drawings, the sprinkler comprises a generally cylindrical body 1 adapted, when in use, to be disposed with its axis vertical; said body being formed with an upper chamber 2 and a lower chamber 3 separated by a horizontal partition 4.

At its lower end the body 1 is tapped for threading engagement with the upper end of a vertical stand pipe 5, through which a water stream is adapted to be delivered, under pressure, into the lower chamber 3.

A plug 6 is threaded into the initially open, upper end of the body 1 and includes a bearing neck 7 through which a tubular stem 8 extends in axially slidable, rotatable relation. The up-

per end portion of this stem forms the sprinkler head, indicated generally at 9, which head is normally disposed, in protective relation, within the bearing neck 7, as shown in Fig. 1. The head 9 includes a transverse, fan spray slit 10 in the closed upper or outer end of said stem, and a pair of opposed, upwardly and outwardly divergent jet openings 11 are formed in said head directly below the slit 10. The bore of the stem 8, within the head 9 thereof, is somewhat reduced in diameter, as at 12, whereby to create a certain amount of back pressure in the lower portion of said stem, for the reason hereinafter described.

Within the upper chamber 2 the lower end portion of the stem 8 is increased somewhat in diameter, whereby to form a stop shoulder 13, and a washer 14 surrounds the stem directly above and bears against said shoulder.

A rotary impeller, indicated generally at 15, is turnably mounted on the lower end portion of the stem 8, and includes a plurality of outwardly extending, circumferentially spaced impeller vanes 16. Escape of the rotary impeller 15 downwardly from the stem 8 is prevented by a plurality of circumferentially spaced, radially outwardly projecting bosses 17 which bear against the underside of an enlarged, annular bottom flange 18 which the rotary impeller 15 includes; the underside of said bottom flange 18 being formed as an arcuate, undulate cam 19, each undulation of which is relatively shallow, and of substantial length.

In the present embodiment there is an undulation of the cam corresponding to each of the bosses 17. The bosses 17 thus constantly bear against or ride the undulate cam 19 in supporting relation to the rotary impeller 15. It should also be noted that the enlarged annular bottom flange 18 forms a closure between the lower ends of the vanes 16.

At its lower end the tubular stem 8 is notched, as at 21, at circumferentially spaced points, with the notches opening downwardly, whereby to provide communication between the upper chamber 2 and the interior of the stem 8 when the latter is in its lowered position, with said lower end of the stem seating on the partition 4. Such partition 4 is formed, centrally thereof, with an upwardly discharging nozzle 20 which communicates with the lower chamber 3.

When water under pressure is introduced from the stand pipe 5 into the lower chamber 3, it is discharged, at relatively high velocity, through the nozzle 20, whence it enters the stem 8, as a jetted stream, from below. This jetted stream

flowing upwardly in the stem 8 and into the reduced-diameter bore 12, causes said stem to rise from its normally lowered position of Fig. 1, to its raised operative position of Fig. 2, in which latter position the head 9 is exposed for operation. The above describes the novel manner in which the pop-up feature of the head 9 is accomplished. With the stem 8, and its head 9, popped up or raised to operative position, rotation is imparted to said stem and head as follows:

Opposed bores 21 lead from opposite sides of the lower chamber 3 into vertical water passages 22 formed in the body 4 on opposite sides thereof. At their upper ends the vertical water passages 22 each communicate with a corresponding duct 23 which leads into the upper chamber 1, adjacent its upper end, on opposite sides thereof and substantially tangential to the vanes 16 of the rotary impeller 15.

It will be seen that with water under pressure flowing from chamber 3 through opposed bores 21 into the vertical water passages 22, and thence through the tangential ducts 23, such water will be projected, as pressure streams, against the vanes 16, causing relatively high speed rotation of said impeller 15. This high speed rotation of the impeller 15 is not fully imparted to the stem 8, but rather a relatively slow rotation of said stem results by reason of the undulate cam 19 running in frictional engagement with the bosses 17. There is of course a high slippage between the undulate cam 19 and the bosses 17, which accounts for the desirable relatively slower rotation of the stem 8, as compared to said impeller 15.

By reason of the fact that the enlarged annular bottom flange 18 forms a closure between the lower ends of the vanes 16, a downward pressure is exerted on said flange when the device is in operation, which downward pressure maintains the undulate cam 19 in proper working engagement with the opposed bosses 17.

After the water leaves the tangential ducts 23, and works the impeller 15, said water flows, within the upper chamber 2, downwardly to entry into the stem 8, whence it flows upwardly with the jetted stream from nozzle 20 for discharge through the sprinkler openings of the head 9.

After use of the sprinkler and shutting off of the water pressure, the stem and impeller unit fall back to their starting positions by gravity, at which time the head 9 is again in its protected position in the bearing neck 7.

It will be recognized that by reason of the described structural arrangement, popping up and rotation of the head 9 is automatically accomplished, upon introduction of water under pressure, into the sprinkler; and further, the design of such sprinkler is such that foreign substance such as sand, which may enter the sprinkler during use thereof, cannot cause any blocking or malfunctioning of the device.

From the foregoing description it will be readily seen that there has been produced such a device as substantially fulfills the objects of the invention as set forth herein.

While this specification sets forth in detail the present and preferred construction of the device, still in practice such deviations therefrom may be resorted to as do not form a departure from the spirit of the invention, as defined by the appended claims.

Having thus described the invention, the following is claimed as new and useful, and upon which Letters Patent are desired:

1. In a sprinkler head which includes a hollow

body having a water inlet and a nozzle member mounted for rotation relative to the body and which nozzle member has a stem projecting into said body; a means for effecting rotation of such nozzle member, such means comprising a water actuated impeller turnably mounted on the stem within the body, and a slip-drive connection between the impeller and stem operable to rotate the stem at a relatively slower speed than that of the impeller, the stem of the nozzle member being movable vertically through the upper wall of the body, the side wall of the body being provided with transversely disposed bores adjacent its upper end, the impeller normally lying below the horizontal plane of the bores when the stem is in its lower position, and said impeller being lifted into said plane upon vertical movement of the stem, and conduit means for supplying water under pressure to said bores.

2. A sprinkler head as in claim 1 in which the impeller includes circumferentially outwardly projecting vanes, and a closure flange between the lower ends of said vanes, said flange lying below the horizontal plane of the said bores when the impeller is raised.

3. In a sprinkler head which includes a hollow body having a water inlet and a nozzle member mounted for rotation relative to the body and which nozzle member includes a tubular stem projecting into such body; a means for effecting rotation of such nozzle member, such means comprising a water actuated impeller turnable on the stem within the body, conduit means to admit water under pressure into the body and against said impeller, a boss mounted on and projecting radially out from the bottom of the stem and a downwardly facing undulate cam on the impeller bearing against the boss.

4. In a sprinkler head which includes a hollow body and a nozzle member mounted for rotation relative to the body and which nozzle member includes a stem projecting into the body and being movable vertically relative thereto; a means for effecting rotation of the nozzle member, such means including a second hollow body about the first body, means to admit water under pressure into the second body, a water nozzle opening through the bottom of the first body into the second body, the stem resting adjacent said nozzle when in its lower position and being liftable vertically in response to water under pressure moving through said nozzle, opposed bores in the side wall of the first body adjacent the top wall thereof and opening communication between the first and second bodies, an impeller mounted about the lower end of the stem and connected in driving connection therewith, said impeller being disposed below the plane of the opposed bores when the stem is in its lower position, such impeller being carried vertically into the plane of such bores when the stem moves vertically.

JOHN A. ROYER.
